US0D1064758S

(12) **United States Design Patent** (10) **Patent No.:** **US D1,064,758 S**
(45) **Date of Patent:** **** Mar. 4, 2025**

(54) **MOLD FOR COOKING**

(71) Applicant: **POTAMA Co., Ltd.**, Okinawa (JP)

(72) Inventor: **Katsuaki Kiyokawa**, Okinawa (JP)

(73) Assignee: **POTAMA CO., LTD.**, Okinawa (JP)

(**) Term: **15 Years**

(21) Appl. No.: **29/811,662**

(22) Filed: **Oct. 15, 2021**

(30) **Foreign Application Priority Data**

Apr. 16, 2021 (JP) ..... 2021-008108 D

(57) **CLAIM**

The ornamental design for mold for cooking as shown and described.

DESCRIPTION

FIG. 1 is a perspective view of a mold for cooking;

FIG. 2 is a front view thereof;

FIG. 3 is a back view thereof;

FIG. 4 is a right-side elevation view thereof, shown in enlarged scale, the left side being a mirror image thereof;

FIG. 5 is a top plan view thereof, shown in enlarged scale;

FIG. 6 is a bottom plan view thereof; and,

FIG. 7 is a cross-sectional view thereof, taken along line 7-7 in FIG. 5.

1 Claim, 7 Drawing Sheets
